UNITED STATES PATENT OFFICE.

GEORGE C. L. TISCH, OF ELIZABETH, NEW JERSEY, ASSIGNOR TO TISCH MACHINE & TOOL & DIE WORKS, INC., OF ELIZABETH, NEW JERSEY, A CORPORATION OF NEW JERSEY.

JACQUARD-DRUM.

1,389,398.

Specification of Letters Patent. Patented Aug. 30, 1921.

Application filed May 18, 1920. Serial No. 382,426.

To all whom it may concern:

Be it known that I, GEORGE CHRISTIAN LOUIS TISCH, a citizen of the United States, and a resident of Elizabeth, in the county 5 of Union and State of New Jersey, have invented a new and Improved Jacquard-Drum, of which the following is a full, clear, and exact description.

This invention relates to jacquard drums, 10 and has for an object the provision of an improved construction wherein a drum or wheel structure is used for holding the pins, instead of an ordinary link structure.

Another object of the invention is to provide a pair of spaced wheel structures 15 formed with a series of radiating openings to take the place of a jacquard link in a knitting machine or loom and to bring the pins opposite the needle bars at the proper 20 time and with accuracy.

A still further object of the invention is to provide knitting machines and the like with a jacquard drum formed with means 25 for carrying a series of pins capable of acting on the needle bars correctly, the construction preventing any appreciable tilting or loose side motion of the pins.

In the accompanying drawings—

Figure 1 is an elevation of a jacquard 30 drum disclosing an embodiment of the invention, a driving mechanism being shown in connection therewith.

Fig. 2 is a top plan view of the construction shown in Fig. 1.

Referring to the accompanying drawings 35 by numeral, 1 indicates a drive mechanism, which is fully described and claimed in my Patent No. 1,381,031, issued June 7, 1921. This driving mechanism is connected with 40 the shaft 2 so as to rotate the same intermittently in order to bring the respective pins 3 opposite the various thread carrying

bars 4. The pins 3 are arranged in apertures in the drum 5, said apertures being positioned to coact with the driving mechanism 1 so that at proper intervals a new set of pins 3 will be brought opposite the bars 4. The drum 5 preferably is formed with a pair of spaced wheels 6 and 7 joined by a tubular body 8, which is preferably integral 50 with the wheels 6 and 7. Set screws or other fastening means 9 secure or clamp the drum 5 rigidly to the shaft 2.

In the drawing ten series of radial apertures are provided for the pins 3, but it will 55 be evident that a greater or a less number could be provided without departing from the spirit of the invention. Where a different number is provided, the driving mechanism 1 must be adjusted to take care 60 of the different number or series of apertures.

What I claim is:

1. A jacquard drum comprising a body and a plurality of spaced wheels, each wheel 65 having a plurality of series of radiating pin receiving apertures, the apertures in one wheel being in line with the apertures in the adjacent wheel.

2. A jacquard drum comprising an integral structure formed with a pair of parallel wheels and a connecting tubular body at the center, said wheels having series of registering apertures, each series being arranged on a line radiating from the center. 70

3. A jacquard drum comprising a tubular body formed with a pair of spaced radiating flanges presenting wheel structures, each flange having radiating rows of apertures registering with the rows of apertures in the 80 other flange, and slidably pins mounted in said apertures.

GEORGE C. L. TISCH.
